Inventor

L. Simmons

UNITED STATES PATENT OFFICE

LEO SIMMONS, OF WASHINGTON, DISTRICT OF COLUMBIA

SHAVING BRUSH AND THE LIKE

Application filed January 29, 1929. Serial No. 335,805.

This invention relates to shaving brushes, and the objects and nature of the invention will be readily understood by those skilled in the art in the light of the following explanation of the accompanying drawings that illustrate what I believe to be the preferred mechanical expression or embodiment of my invention from among other forms, constructions, and arrangements within the spirit and scope thereof.

An object of the invention is to provide a shaving brush the parts of which including the bristle tuft can be readily cleansed as well as separated for renewal, inspection and washing, and wherein a trap or receptacle is provided to receive and retain lather and soap solution, particularly when the brush is held or standing in reversed position, and thereby protect the handle and hands.

With the foregoing and other objects in view, my invention consists in certain novel features in construction, assembly and combination, as more fully set forth and specified hereinafter.

Referring to the accompanying drawings, forming a part hereof;

Fig. 1 shows in perspective a shaving brush and the like embodying my invention.

Fig. 2 is a longitudinal section.

Fig. 3 shows parts of the brush separated and in longitudinal section.

The brush member or element consists of a usually flat-faced disk-like hard rimmed head or body 2, usually of plastic or other material in which the bristle ends are permanently embedded and thereby anchored and secured to form the bundle of bristles 1, constituting the bristle tuft for lathering and rubbing. This head 2, as a permanent part thereof, includes a cylindrical surrounding ring or band 3, preferably of metal, that is annularly flanged inwardly at its top edge to provide the head with a radially enlarged annular rim forming the top annular shoulder 4.

It is contemplated that users of my improved shaving brush, will be able to purchase in the open market for replacement purposes, the brush members or elements substantially as herein described and shown,

having brush hairs or bristles of different qualities and characteristics to suit various individual preferences.

My invention also contemplates means whereby such brush member or element can be removably and operatively associated with a suitable handle and guard cup or receptacle, to provide a complete shaving brush possessing certain novel and advantageous characteristics.

For instance, I show a longitudinally elongated handle 5, formed by a block of suitable strong usually hard material, that is preferable non-absorbent, and preferably capable of being smoothly finished and polished. This handle is formed with a central longitudinal bore or bolt hole 5^a.

The transverse end of the handle adjacent the brush member, i. e. the upper end of the handle, is hollowed out or concaved, to form an upwardly or outwardly facing cup-like receptacle 5^b, of substantial capacity, concentric with the longitudinal axis of the handle. In the particular example illustrated, the end of the rigid handle that forms this receptacle, is of relatively enlarged diameter and is molded, machined, or otherwise shaped, to provide an annular outwardly and upwardly flaring rigid flange 5^c, integral with the body of the handle, to constitute the open-top cup or receptacle 5^b, provided by the peculiar end formation of the handle itself.

A screw-threaded rod or bolt 6 is removably and longitudinally fitted in the bore 5^a, of the handle 5, and removably secured therein by the screw threaded nut 6^a, removably fitting the outer (lower) end of the handle and longitudinally receiving and screwing on the threaded outer end of bolt 6. The nut 6^a is preferably formed to centrally fit on and overlap the adjacent end face of the handle, and the outer face of said nut is preferably flat and of sufficiently extensive area to form the base on which the shaving brush can stand in upright position.

The inner (upper) end of the bolt 6, is formed with a rigid head 7, arranged centrally and longitudinally within the end cup 5^b, and of materially reduced diameter with respect thereto to reduce to the minimum the reduc-

tion in cup capacity resulting from the partial location of the head therein. This head 7, at its lower end, provides a preferably flat annular transverse face 7^a, to abut the central 5 portion of the floor of the cup surrounding the upper end of bore 5^a, to close the upper end of said bore, and to provide an abutment opposing nut 6^a, whereby the handle and bolt can be tightly clamped together. The head 10 7, is of greater length than the depth of the cup 5^b, and at its free or upper end forms a transverse circular disk-like portion 7^b, longitudinally screw threaded at its cylindrical periphery and having a transverse flat top 15 face to receive the flat bottom face of the rimmed head 2, of the bristle tuft. The diameter of said head 2, is approximately the same as the diameter of disk portion 7^b, and suitable means is to provide for removably 20 clamping or coupling the brush member head 2, to or against the portion 7^b, in operative shaving brush relation. For instance, for this purpose, in the particular example illustrated, I show, a removable flanged screw 25 threaded coupling sleeve 8.

This sleeve is annularly flanged inwardly at its upper end, at 8^a, and is interiorly screw threaded at its lower end, where the interior diameter of the sleeve approximately equals 30 the diameter of portion 7^b, to longitudinally screw thereon. The length of the sleeve 8, exceeds that of the bristle tuft head, and the internal diameter of said sleeve is such that 35 the sleeve can be longitudinally slipped onto and from and along the bristle tuft 1, and over and to snugly cover the head 2, while the reduced diameter at the upper end of the sleeve at flange 8^a, provides an annular shoulder to cover and abut shoulder 4, of the head 40 2, whereby the bristle tuft head is retained and tightly clamped against disk portion 7^b, when the sleeve 8, is screwed down on said portion. The sleeve is preferably exteriorly 45 knurled or otherwise formed, at 8^b, to facilitate screwing and unscrewing the sleeve by the fingers, to clamp and release the brush member. The disk portion 7^b, is of substantially reduced diameter with respect to the 50 top diameter of cup 5^b, and the portion of head 7, below said disk is of substantially reduced diameter, as the purpose is to provide a cup of substantial capacity. The provision 55 of the upwardly flaring cup, as a rigid part of the upper end of the handle, in this example with the brush head mounting of reduced diameter with respect thereto, provides an annular opening between said mounting and the top edge or rim of the cup, through which 60 lather and soap solution flowing down the brush head mounting, can drip into and will be caught by the cup, to protect the handle and hand grasping the same. This arrangement also facilitates washing and cleansing 65 the shaving brush, as flowing water from a

faucet has free access to the cup and other parts of the complete brush.

By unscrewing and removing nut 6^a, the handle and bolt can be separated for cleansing, and for replacement of worn or damaged parts.

In the example shown, the cylindrical exteriorly screw threaded member 7 is normally secured as a stationary part of the handle 5 located in the cup 5^b and thus provides the handle with a screw threaded portion centrally arranged with respect to the cup, to which the rimmed head of the bristle tuft is removably clamped by the coupling sleeve 8, as hereinbefore described so that the bristle tuft can be removed and replaced by manipulation of the coupling sleeve while the externally screw threaded disk or head 7 remains in fixed position as a part of the handle.

In the example shown the member 7 that provides a seat against which the bristle tuft head is clamped by the coupling sleeve 8, is removably secured in fixed relation to the handle 5 by a screw threaded connection consisting of the threaded bolt 6 and its complementary nut 6^a.

I do not wish to limit my invention to the approximate disclosure hereof except where required by the following claims construed in the light of the prior art, as various changes, modifications and departures can be resorted to.

What I claim is:

1. A brush, embodying a handle having a rigid end cup of enlarged diameter and a longitudinal cylindrical threaded end portion secured to said handle and of reduced diameter and centrally arranged with respect to said cup, said threaded portion providing an end seat; a bristle tuft provided with a rimmed head having an end abutment face adapted to said end seat; and a removable screw thread coupling sleeve of reduced diameter with respect to said cup and loosely fitting said head to screw on said portion and rigidly clamp the head and handle together with said seat directly abutting said abutment face whereby the bristle tuft can be clamped to and removed from the handle by screwing said sleeve onto and from said threaded end portion.

2. A shaving bristle tuft embodying a brush having a permanent rimmed head; a handle; a bolt having means for removably securing the handle thereto; said bolt having a projecting end head providing a cylindrical exteriorly screw threaded end portion providing an end face against which the end face of said rimmed head fits; and a screw threaded removably coupling sleeve normally surrounding said rimmed head and screwed on said threaded end portion and fitting the rimmed head to clamp the same against said end face, whereby said bristle

tuft is separable from said bolt head and said handle.

3. A shaving brush embodying a handle having a longitudinal bore and providing a rigid end cup of enlarged diameter; a bolt arranged in said bore and removably secured to the handle, said bolt having an end head arranged centrally and longitudinally in said cup and formed with a screw threaded cylindrical end; a removable bristle tuft having a permanent rimmed cylindrical end head normally seated against said cylindrical end; and a screw threaded coupling sleeve removably screwed on said cylindrical end and engaging said rimmed head to clamp the bristle tuft against said cylindrical end in operative normally fixed relation to said handle and its cup.

Signed at Washington, D. C., this 28th day
20 of Jan., 1929.

LEO SIMMONS.
